[57] CLAIM

The ornamental design for a golf putter grip, as shown and described.

DESCRIPTION

FIG. 1 is a front elevational view of a golf putter grip showing our new design;

FIG. 2 is a side elevational view of the golf putter grip taken from the right in FIG. 1, the opposite side elevational view taken from the left in FIG. 1 being a mirror image thereof; FIG. 3 is a rear elevational view of the golf putter grip shown in FIG. 1;

FIG. 4 is a top end view of the golf putter grip shown in FIG. 1;

FIG. 5 is a bottom end view of the golf putter grip shown in FIG. 1; and,

FIG. 6 is a front elevational view of a golf putter grip according to an additional embodiment of our new design; the side elevational views, the rear elevational view, the top end view and the bottom end view of this additional embodiment being identical to FIGS. 2, 3, 4 and 5, respectively.
